FIG. 1.

FIG. 2. Ernest C. Keithley
INVENTOR

BY

O. V. Thiele

ATTORNEY

UNITED STATES PATENT OFFICE

ERNEST C. KEITHLEY, OF DETROIT, MICHIGAN, ASSIGNOR TO THE SUPERHEATER COMPANY, OF NEW YORK, N. Y.

BOILER

Application filed September 30, 1927. Serial No. 223,032.

This invention relates to boilers and particularly to boilers in which one or more furnace walls are equipped with water screens. It has for its purpose the provision of such a boiler in which a superheater is placed between the water screen and the wall and in which provision is made whereby the degree of superheat can be controlled. Other and more detailed objects of the invention will 10 appear from the following description.

The invention is illustrated in the single sheet of drawings herewith in which Fig. 1 is a side elevation, partly in vertical longitudinal section, of a boiler with the invention applied; Fig. 2 is a fragmentary section on an enlarged scale on line 2—2 of Fig. 1; and Fig. 3 is a fragmentary section on an enlarged scale on line 3—3 of Fig. 1.

The boiler in which the invention is shown 20 in the drawing is of the so-called horizontal water tube type. Some of these water tubes are visible at 1. They communicate at their two ends with the headers 2 and 3. The major portion of this boiler is hidden by the 25 wall 4 of the setting. 5 is the steam and water drum of the boiler from which the steam is taken off through the pipe 6. The furnace below the boiler is enclosed by front wall 7, rear wall 8, and two lateral walls (only 30 one of which appears at 9, the other being removed in the section).

To illustrate the invention it is shown applied to the wall 9, but it will be obvious from the ensuing description that it may equally well be applied to the other side wall and to the rear wall 8. In practice it will usually be applied to the two side walls only. The screen referred to in the introductory remarks above comprises a series of parallel vertical water tubes 10. The lower ends of these are secured to and communicate with the interior of the lower header 11, while their upper ends are secured to the upper header 12 and communicate with its interior. The lower header 11 communicates with the boiler space by means of the pipe 13, the cross box 14 and the nipples 15. The upper header 12 is in communication with the boiler through the pipe 16, cross-pipe 17, and nipples 17a.

Between the screen tubes 10 and the wall 9 are arranged the superheater tubes 18. These are straight for the major portion of their length but are bent outward through the wall 9 at their lower and upper ends and connected to the lower and upper headers 19 and 20 respectively. The lower header 19 receives the steam from the steam drum 5 through the connecting pipe 21, while the superheated steam is taken off from the upper header 20 through the connection 22 and carried to the point of use.

At 23 is shown one of the pulverized fuel burners the flame from which travels downward at first and then toward the left and upward into the furnace space proper. From here the hot gases travel over the boiler surfaces and finally out through the stack connection 24.

At the present stage of the art of superheating it is very difficult to predict accurately the degree of superheat which will be obtained in a radiant type of superheater. It is for this reason highly desirable to have some means whereby the degree obtained when the boiler is put into service may be readily corrected to approximate that computed in advance from theoretical considerations. A further advantage of the invention is that if a change in conditions is made after the boiler is put into operation, such, for example, as a change in the character of the fuel, which might entail a change in the degree of superheat obtained, a suitable adjustment can readily be made to bring the superheat back to the desired point.

The means proposed for this purpose consist in a wall or partition 25 placed between the superheater elements 18 and the water tubes 10 of the section. This wall is made up of bricks 26 of fire resisting material. It rests upon a ledge 27 secured to the wall 9. Evidently the height of the wall 25 will directly affect the degree of superheat obtained and a variation in this height presents a ready means for adjusting the degree of superheat. If it is found, for example, that the superheat is somewhat too high, the wall can be built up a little more. If at some time in the operation of the boiler a fuel is used

which tends to raise the degree of superheat, the wall can also be raised. On the other hand if the degree of superheat is too low, the wall can be partially removed.

5 In the form shown the wall covers the lower portion of the superheater and this will generally be the most convenient place to install it, but it will be obvious that if desired this wall can readily be secured between the water tubes and the superheater tubes over some other area, for instance, nearer the top or only near the front or only near the rear of the furnace. Such a variation is considered to be within the scope of 15 this invention. Other variations will readily occur in practice.

I claim:

1. In a boiler, the combination of a furnace wall; a series of spaced water tubes parallel to and in proximity to the wall; a superheater between the water tubes and the wall; and a partition of adjustable size between the water tubes and the superheater, whereby the amount of the superheater surface exposed to radiant heat, and therefore the degree of superheat, can be adjusted.

2. In a boiler the combination of a furnace wall; a plurality of spaced aligned vertical water tubes parallel to and in proximity to the wall; a plurality of aligned superheater tubes parallel to the water tubes and between them and the wall; and a partition comprising separate heat-resisting blocks between the water tubes and the superheater tubes and supported laterally by them; the extent of said partition, and therefore the degree of superheat, being adjustable.

3. In a boiler the combination of a furnace wall; a plurality of spaced, aligned, vertical water tubes parallel to and in proximity to the wall; a plurality of aligned superheater tubes parallel to the water tubes and between them and the wall; and a partition extending upward from the lower ends of the superheater tubes between them and the water tubes and supported laterally by them; the height of said partition and therefore the degree of superheat being readily adjustable.

4. In apparatus of the class described, the combination of a boiler; a furnace under the boiler; walls enclosing them; a row of spaced vertical water tubes parallel to and near one of the walls; a superheater comprising top and bottom headers outside of the furnace and parallel to the last-named wall, and tubular vertical elements between the said wall and said water tubes, their ends bent toward and connected to the headers; a wall between the superheater elements and the water tubes, shielding the elements from radiant heat from the furnace; the height of said wall and therefore the degree of superheat being adjustable; and a support secured to the furnace wall to support said adjustable wall.

65 ERNEST C. KEITHLEY.
